US00D422925S

United States Patent [19]

Glaser et al.

[11] Patent Number: Des. 422,925

[45] Date of Patent: ** Apr. 18, 2000

[54] CHROMATOGRAPH

[75] Inventors: **Michael David Glaser**, The Woodlands, Tex.; **James Ward Baker**, Elkton, Md.; **Roger A. Brown**, Philadelphia; **Ellen F. Mason**, Narberth, both of Pa.; **Thomas E. Price**, St. Georges; **Thomas M. Przybylski**, Newark, both of Del.; **Robert P. Rhodes**, Lincoln University, Pa.; **George P. Walsh**, Wilmington; **William H. Wilson**, Newark, both of Del.

[73] Assignee: **Hewlett-Packard Company**, Palo Alto, Calif.

[**] Term: **14 Years**

[21] Appl. No.: **29/095,677**

[22] Filed: **Oct. 28, 1998**

[51] LOC (6) Cl. **10-04**

[52] U.S. Cl. **D10/81**

[58] Field of Search D24/232; D10/81; 95/23, 82, 87, 89; 73/23.24, 23.26, 23.41, 23.42, 23.35; 422/89; 96/105, 102, 101

Primary Examiner—Stella Reid

[57] CLAIM

The ornamental design for a chromatograph, as shown and described.

DESCRIPTION

FIG. 1 is a perspective view of chromatograph, showing our new design;

FIG. 2 is a front elevational view;

FIG. 3 is a rear elevational view;

FIG. 4 is a top plan view;

FIG. 5 is a bottom plan view;

FIG. 6 is a right side elevational view; and,

FIG. 7 is a left side elevational view.
